UNITED STATES PATENT OFFICE.

EINAR G. C. LOFGREN, OF MINNEAPOLIS, MINNESOTA.

TELETYPEWRITER OR PRINTING-TELEGRAPH.

1,348,430.

Specification of Letters Patent.

Patented Aug. 3, 1920.

Application filed April 21, 1916. Serial No. 92,646.

To all whom it may concern:

Be it known that I, EINAR G. C. LOFGREN, a subject of the King of Great Britain, residing at Minneapolis, in the county of 5 Hennepin and State of Minnesota, have invented certain new and useful Improvements in Teletypewriters or Printing-Telegraphs; and I do hereby declare the following to be a full, clear, and exact description 10 of the invention, such as will enable others skilled in the art to which it appertains to make and use the same.

This invention relates to improvements in telegraph typewriters.

15 The object of the present invention is to improve the construction of telegraph typewriters and to provide simple, practical and highly efficient mechanism adapted to be readily applied to various styles of typewriting machines of standard make and adapted to be operated by a typewriting machine at the transmitting end of the line and of simultaneously actuating electrically a typewriter at the receiving end of the line 20 so that a permanent record may be made in typewriting on each machine.

25 A further object of the invention is to provide telegraph typewriter mechanism adapted to be operated over a single main line or circuit and capable of enabling the typewriting machine to be operated independently of the electrical actuating means and without injury to the latter.

30 With these and other objects in view, the invention consists in the construction and novel combination of parts hereinafter fully described, illustrated in the accompanying drawings, and pointed out in the claims hereto appended; it being understood that 35 various changes in the form, proportion, size and minor details of construction, within the scope of the claims, may be resorted to without departing from the spirit or sacrificing any of the advantages of the invention.

40 In the drawings

45 Figure 1 is a diagrammatic view of the circuits of the transmitting typewriter.

50 Fig. 2 is a transverse sectional view, illustrating the arrangement of the keys or key levers, of the transmitting typewriter and the contacts operated by the said keys or key levers.

55 Fig. 3 is a detail view illustrating the arrangement of the carriage actuating solenoid or magnet and gearing,

Fig. 4 is a plan view of the electrical mechanism for actuating the keys or key levers of the receiving typewriter,

Fig. 5 is an elevation of the arcuate switch 60 and the oscillatory contact arm or member,

Fig. 6 is a detail view of the mechanism for operating the switch for controlling the magnets or solenoids of the two sets of keys or key levers,

Fig. 7 is a vertical sectional view taken longitudinally of the mechanism of the receiving typewriter,

Fig. 8 is a diagrammatic view partly in perspective illustrating the instrumentalities and the wiring of the same of both the sending and receiving typewriters.

Fig. 9 is a detail sectional view of the spring actuated locking lever,

Fig. 10 is a detail view of one of the keys.

Like numerals of reference designate corresponding parts in the several figures of the drawings.

In the accompanying drawings in which is illustrated the preferred embodiment of 80 the invention, the transmitting typewriter is equipped with an interrupted local circuit, and induction coils in the transmitting and receiving typewriter which enable a switch of one-half the size and number of 85 contacts to be employed for controlling the key actuating magnet of the receiving typewriter. The key board of the transmitting typewriter has its keys arranged in two sets, the sets being referred to as upper and lower 90

sets and designated respectively by the numerals 1 and 2 and provided with depending contact arms or portions 3 having roller contacts 4 adapted to reduce friction to a minimum but any other suitable form of 95 contact may be employed as will be readily understood. The transmitting typewriter is equipped with a resistance 5 preferably in the form of a coil from which extend conducting wires 6 having branches 7 and 8 connected with contacts 9 and 10 consisting of approximately L-shaped spring plates and located beneath and in the path of the contacts of the keys or key levers whereby

when a key is depressed a connection will 100 be made between the key and one of the branches of the conducting wires 6 of the resistance. The resistance coil 5 is connected with the secondary winding 11 of an induction coil 12 by a wire 5^a and the said 105 secondary winding is connected with the wire 13 of the main line circuit by a wire 5^b

so that when anyone of the typewriter keys of the transmitting instrument, which keys are connected with the wire 13^a of the main line circuit, is depressed the main line will 5 be closed and a current will be passed through the resistance coil and by means of the mechanism hereinafter described each of the conducting wires 6 of the resistance coil is connected with two keys, one in each 10 set thereby reducing the number of contacts and the size of a key selecting switch, one-half.

The keys of the upper set comprising the two upper rows of keys or key levers simply 15 close the main line circuit through the resistance coil but the keys of the lower two rows or sets also close in addition thereto contacts 14 and 15 consisting of spring plates having contiguous substantially parallel upper portions located in the path of the contacts carried by the keys of the lower set and adapted to be closed by the depression of the said key of the lower set. The contacts 14 and 15 are connected by wires 20 25 16 and 17 with the primary winding 18 of the induction coil 12 to form a local circuit which is closed simultaneously with the main line circuit when a key in the lower set is depressed and which includes a battery 18^a. An interrupter 19 is placed in circuit 30 35 with the primary winding of the induction coil in the local circuit for causing ripples or impulses in the primary winding for inducing a current in the secondary winding 35 for operating a switch in the mechanism of the receiving typewriter as hereinafter fully explained.

The main line or circuit may consist of a single wire grounded or a return wire may 40 45 be employed as will be readily understood and the contact roller 4 is connected with the wire 13^a of the main line which may be effected by an insulated wire 4^a extending from the contact roller or wheel 4 to the wire 4^b which is connected to the wire 13^a or the body of the key may be used as a conductor and the wire 4^b of the main line may then be connected to the key. Binding posts 21 are provided for the wires of 50 55 the main line or circuit and other binding posts 22 are provided for the local circuit and a battery 13^b is included in the main line circuit. When the keys are employed as conductors suitable insulating caps (not shown) will be provided.

The keys of the receiving typewriter are arranged in upper and lower sets 24 and 25 which are connected with cores 26 and 27 of solenoids 28 and 29 but instead of employing solenoid magnets, electromagnets having fixed cores may of course be employed as will be readily understood. The separate sets of key actuating magnets are connected by wires 31 and 32 with separate 60 65 sets of contacts 33 and 34 located above and

below a single set of contacts 35 which is adapted to engage with either of the sets of contacts 33 and 34 for connecting the separate sets of key actuated magnets with means for energizing the magnets, one set 70 or the other of the separate sets of magnets being connected with the said means. By means of wires 31^a and 32^a, the solenoids 28 and 29 are connected to a wire 32^b leading from the battery 49^a. The contacts 33 and 75 80 85 90 95 100 105 110 115 120 125 130 34 are mounted on a pivoted bar or member 35^a to which is connected a lever 36 which is actuated by a core 37 of a solenoid 38 for partially rotating the said member 35^a to carry either set of contacts 33 and 34 into engagement with the single set of contacts 35. The vertical solenoid 38 which is arranged in circuit with the secondary winding 39 of an induction coil 40 is connected with the said secondary winding by wires 85 which constitute a local circuit 41 for the receiving typewriter. The primary winding 42 of the induction coil 40 is arranged in circuit with the main line or circuit by wires 13^c and 13^d so that when ripples or oscillations are caused by the closing of the local circuit of the transmitting typewriter the induced current will cause corresponding oscillations or electrical impulses in the secondary winding of the induction coil 40 for operating the solenoid 38 and moving the switch member 35^a so that the lower contacts 34 will be moved out of engagement with the contacts 35 and the upper contacts 33 will be moved into engagement with the contacts 35. A spring 35^b is connected to the lever 36, and is adapted to normally hold the lower contacts 34 in engagement with the contacts 35. The magnet controlling switch is locked in its depressed position by means of a catch 43 consisting of a lever fulcrumed at 44 and provided with an engaging portion 45 adapted to be carried into the path of the lever 36 by a spring 46. The engaging portion 45 is preferably in the form of a tooth beveled at the upper portion or edge and having a lower shoulder. This will enable the lever to pass the tooth on the downward movement and to be locked against upward movement. The catch or lever 43 is provided with a curved arm 47 which is arranged in the path of a pivoted oscillatory contact arm or member 49 of a key selecting switch 50. The key selecting switch 50 comprises an arcuate guiding frame or partial casing 51 having upper and lower guide plates or flanges 52 and 53 and provided at intervals with contact plates 54 which are connected by wires 55 with the fixed contacts 35 of the single set of the magnet controlling switch. The guide frame or casing 51 may be constructed of insulating material or the contact plates may be mounted in suitable insulation and their lower edges 56 (see Fig. 5) are bev-

eled as shown to assist in guiding a roller 57 of the contact arm or member 49 into engagement with the contact plates and the said roller is adapted to move upwardly on 5 the contact plates 54 when the depressed key is released as hereinafter fully explained to close the local key magnet circuits for actuating the key or key lever of the receiving typewriter to print the required character. 10

The pivoted contact arm or member 49 is mounted at its inner or pivoted end on the upper end of a hollow core 58 of a solenoid 59 arranged vertically and in circuit with the main line. The wires 13^c and 13^d connect the solenoid 59 with the main line wires 13 and 13^a. The arm or member 49 is suitably secured to the hollow core which is slidably mounted on a vertical guide rod 60 15 and which also contains a coiled spring 61 adapted to move the core 58 upwardly and outwardly when the solenoid 59 is deenergized by the opening of the main line circuit through the releasing of the key of the transmitting typewriter. The coiled spring 20 is compressed when the core 58 is moved downwardly and inwardly through the closing of the main line circuit and the pivoted contact arm or member 49 is drawn downwardly from the upper portion of the guide frame 51 to the bottom guide plate 53 when the said solenoid 59 is energized. The particular mounting of the arm 49 permits the latter to oscillate and also to move upwardly 25 and downwardly.

The pivoted arm normally occupies the position shown in Fig. 4 of the drawings at the left hand end of the arcuate guiding frame or casing and it is swung to the right 30 from such position by a horizontally disposed solenoid 62 arranged in the main line or circuit and having a core 63 pivotally connected at 64 to the contact arm or member 49. The solenoid 62 is connected by 35 the wires 13^c and 13^d with the main line wires 13 and 13^a. When the main line or circuit is closed by depressing a key the vertically and horizontally disposed solenoids are energized and the arm or member 49 is 40 first depressed by passing the current through the vertically disposed solenoid and is then swung to the right by the current passing through the horizontally disposed solenoid 62. When the key is released opening the 45 main line circuit, the spring 61 operates to move the contact roller upwardly over one of the contact plates 54 of the key selecting switch 50 thereby energizing the key magnet circuit and operating the key of the receiving typewriter. The pivoted arm or member is returned to its initial position by a spring 65 which is of less strength than the spring 61 so that the latter will respond and move the pivoted arm upwardly before 55 the spring 65 swings the pivoted arm back 60 to its initial position. The magnets or solenoids of the receiving typewriter are preferably arranged at different elevations to enable them to be closely assembled as clearly illustrated in Fig. 7 of the drawings. 70

When one of the keys of the upper set or series of the transmitting typewriter is depressed the main line circuit is closed and the current passes through the resistance coil and through the secondary of the induction coil 12 along the main line to the receiving typewriter passing through the solenoid 59 drawing the pivoted arm and the core 58 of the vertical solenoid 59 downward and passing through the horizontal 80 solenoid 62 to swing the pivoted arm along the arcuate key selecting switch to the proper contact. When the key is released and the main line circuit is open the solenoid 59 is deenergized permitting the coiled spring 61 85 to move the core 58 upwardly and carry the roller 57 over the contact 54 to close the solenoid or magnet circuit of the keys for actuating the particular corresponding key of the receiving typewriter. The pivoted 90 arm 49 may be used as a conductor and the current from the local battery 49^a passed through the same. The arm 49 is connected to the battery 49^a by a wire 49^b and a wire 49^c. The wire 49^c is connected to a 95 suitable binding screw or post 66 at the inner pivoted end of the arm 49. The other connections with the pivoted arm at the spring and the solenoid are of course insulated. As soon as the contact roller of the 100 arm 49 leaves the coacting contact plate 56 the solenoid or magnet circuit will be opened and the depressed key of the receiving typewriter released. After establishing the key operating circuit and depressing the receiving key the arm 49 is swung back by the light spring 65. 105

Each of the wires 6 as previously pointed out is provided with two branches and when a key of the lower branch 8 is depressed, the 110 current passes through the same portion of the resistance coil 5 as when the key of the upper branch 7 is depressed but the contacts 14 and 15 are also closed closing the local circuit of the transmitting typewriter and sending a current through the primary winding or coil of the induction coil 12. This will cause ripples or oscillations in the induction coil and induce a current in the secondary coil which will cause oscillations 115 or ripples in the primary of the induction coil 40 of the receiving typewriter and induce a current in the secondary coil or winding 39 of the induction coil 40. Solenoid or magnet 38 will energize operate the 120 magnet or solenoid controlling switch and carry the movable switch member from the lower contact 53 to the upper contact 52 to cause a current to be sent through a magnet or solenoid of the lower set. The closing 125 130

of the line circuit when one of the upper keys is depressed naturally causes a current in the secondary of the induction coil of the receiving typewriter but it is of too short a duration to act upon the solenoid and operate the core or plunger thereof.

- At the end of each line a key 67 is depressed for sending a current over the main line or circuit around the resistance coil 5.
- 10 The contact 6^a of the key 67 (see Figs. 1 and 8) is connected by a wire 68 with a horizontally disposed solenoid 69 that is also connected by a wire 70 with the wire 5^a (see Fig. 1) that connects the resistance coil 5 with the secondary coil or winding 11 of the induction coil 12. The key 67 is connected to the wire 4^b by a wire 71. The solenoid 69 is adapted to actuate the carriage and move the same from one side of 20 the machine to the other. The solenoid 69 is provided with a core 71^a which is connected by a rod 72 with a pinion 73 mounted upon a fixed rack bar 74 and meshing with a movable rack bar 75 having an arm 76 that is connected with a pinion 77. The arm 76 is approximately L-shaped to arrange the pinion 77 in position to roll upon a fixed rack bar 78 that is located above and extends over the solenoid 69. The pinion 77 30 also meshes with a movable rack bar 79 that constitutes a portion of the carriage, not shown, and when the solenoid 69 is energized the pinions are caused to move along the fixed rack bars and actuate the movable rack bars and increase the movement of the core 71^a sufficiently to carry the carriage of a typewriter from one side of the machine to the other. The receiving typewriter is also equipped with the solenoid 69^a and the 40 mechanism actuated by the same for returning the carriage of the receiving typewriter to the starting point and the solenoid of the carriage actuating mechanism is connected by a wire 80 with a contact 81 located at the 45 extreme right hand end of the key selecting switch in Fig. 4 and with the wire 32^b by a wire 70^a. When a current is sent over the line wire by means of the key 67 past the resistance without going through the 50 same, the pivoted arm or contact member 49 is swung from one end of the guide frame or casing 51 to the other and carried into contact with the contact member 81 thereby closing the circuit of the carriage actuating 55 mechanism. The wires 6, which are connected with keys of the sending typewriter, are connected with the resistance coil 5 at different points along the same so that currents of different strength will be sent over the main line to the receiving typewriter by reason of the current passing through portions of the resistance of different lengths. This will enable the current to operate the horizontally disposed solenoid 62 and move 60 the core 63 different distances so that the 65

pivoted arm 49 of the switch 50 will select the proper contact 54 of the guide frame or casing for operating the proper key of the receiving typewriter.

The circuits through the keys are as follows: When one of the upper set of keys 1 is depressed, the key is carried into contact with the contact 9 (see Fig. 8) and the circuit is closed, the current passing along the wire 6 by way of the branch 7 (see Fig. 1) to the resistance 5, passing through a portion of the same along the wire 5^a to the induction coil 12 through the secondary winding 11 thereof, through the wire 5^b to the main line wire 13 through the wire 13^c, to the primary winding 42 of the induction coil 40 (see Fig. 4), thence to the vertical solenoid 59 through the wire 13^d, thence to the horizontal solenoid 62, thence to the main line 13^a and battery 13^b, and thence through the wires 4^b and 4^a back to the roller contact of the key 1.

Should one of the lower keys be depressed, the contacts 14 and 15 will be closed and a current will be established through the local circuit including the primary winding 18 of the induction coil 12 and the interrupter 19 producing impulses through the main line circuit by reason of the currents induced in the secondary winding 11. This will cause the impulses to be produced in the primary winding 42 of the receiving typewriter and currents or impulses will be induced in the secondary winding 39 (see Fig. 4) and the current will pass through the vertical solenoid 38 which is in circuit with the secondary winding of the induction coil 40 by means of the wires 41. The solenoid 38 will operate the pivoted member 35^a which carries the contacts 33 and 34 and will move the upper contact 33 into engagement with the contact 35 and carry the lower contact 34 away from the contact 35. When the upper contact 33 is in engagement with the relatively fixed contact 35, the current through the solenoid circuit will be through one of the lower set of solenoids and will operate one of the lower keys, and when the lower contact 34 is in engagement with the relatively fixed contact 35, the circuit of the solenoids will include one of the upper set of solenoids and one of the upper keys will be operated.

The current passes from the upper set of keys 1 to the resistance coil 5 thence to the upright solenoid 59 and depresses the switch arm 49 (Fig. 5). By the action of the horizontal solenoid 62 this arm is moved along the insulating path 53 of the switch casing 51 for a distance corresponding to the amount of resistance employed at the transmitting end of the switch. As soon as the transmission key is released, the strong spring 61 causes the switch arm 49 to ascend and establishes electric contact 130

by means of the roller 57 with the respective contact 54 of the switch and which by means of wires 55 is connected to the corresponding stationary contact 35. In operating 5 one of the two sets of keys, the upper set 1 in particular, the current will now pass through 35 to one of the sets of connecting contacts 34 by means of one of the wires 55 and thence by means of one of the wires 31 10 to one of the solenoids 28 of the receiving keys. If on the other hand the other set of transmission keys 2 is operated a branch circuit is established through contacts 10, 14, 15 in addition to the circuit established 15 by the amount of current which passes directly into the switch arm 49 as above pointed out. By the action of the interrupter 19 a pulsating current is generated in the secondary coil 11 which passes 20 through the primary coil 42 of the induction coil 40 and which by means of the secondary coil 39 of this coil 40 causes the solenoid 38 to be energized. This solenoid 38 attracts its core 37 with the armature 25 lever 36 and thereby rotates the rod 35^a which is secured to one end of the armature 36. By the rotation of the rod 35^a, the movable contacts 33 or 34 which are mounted at the outer end of this rod are turned 30 around and changed so as to bring, for instance, the upper set 33 of the movable contacts into direct connection with the stationary contacts 35 and by means of the wire 55 with the switch arm 49. When de- 35 pression of the transmission key has ceased, the armature lever 36 is retained in its depressed position in which it determines the position of one set of movable contacts 33 and 34 respectively, and by means of en- 40 gagement with the pivoted curved arm 47 it will be retained in this operating position as long as the switch arm 49 is in contact with the corresponding contact 54, but as soon as the switch arm 49 has been with- 45 drawn by the light spring 65 the pawl or locking means 47 is released. By means of the spring 46 the pawl 40 is kept in engagement with the armature lever 36. When the switch arm 49 has been moved to the end 50 of its path, it will strike against the free end 47 of the lever 43 thereby swinging said lever or pawl and releasing the armature 36 and thereby also rotating the rod 35^a and restoring the original position of the sets 55 of contacts 33 and 34. When the lower contact is in engagement with the fixed contact 35 the current passes through the arm 49, contact 54, the movable lower contact 34, and to the upper set of solenoids 28 and 60 the battery 49^a. When the rod 35^a has been rotated, as above explained, the other set of movable contacts 33 is turned into operating position, the operation remaining the same with the exception that the cur- 65 rent now passes from the contact 35 to the

contact 33 and thence to the wire 32 energizing the solenoids 29 of the other set of receiving solenoids.

In practice the typewriters will be equipped with the usual mechanism for automatically 70 rotating the platen when the carriage is carried from one side of the machine to the other. A signal bell 84 at the receiving typewriter may be operated by a key 85 at the sending typewriter. The circuit under the 75 control of this key includes a contact 85^a, wire 85^b, resistance 5, wire 5^a, secondary coil 11, wires 5^b, 13 and 18^a, primary coil 42, wires 18^a, 13^a, 4^b and 85^c and contact wheel 85^a. The battery 13^b and the sole- 80 noids 59 and 62 are included in this circuit. The bell circuit includes the battery 49^a, wires 32^b and 84^a, wire 84^b, one of the contacts 34, one of the wires 55, one of the contacts 54, arm 49, and wires 49^c and 49^b. 85 When the key 85 is depressed and released the solenoids 59 and 62 are energized, resulting in the arm 49 moving over that contact 54 which is in the bell circuit and closing such circuit. The bell 84 may be op- 90 erated in code to indicate the character of paper to be employed or to convey any other desired information relative to preparing the receiving typewriter for the reception of a message. In practice the sup- 95 ports or bars 82 upon which the contacts 9, 10, 14 and 15 are mounted (Fig. 2) will be pivoted as shown at 83 to permit the contacts to be swung downwardly out of the path of the depending contacts of the keys 100 so that the transmitting typewriter may be operated without wearing the contacts when the machine is used for ordinary type- writing and not for sending messages.

105

What is claimed is:—

1. Printing telegraph including a key selecting switch comprising substantially parallel guides and contacts located between the guides, an oscillatory contact arm or member arranged to swing longitudinally of the switch and movable between the guides over the contacts, a solenoid having a core constituting a pivot for the movable arm or member, key actuating magnetic means connected with the said contacts, an electromagnet connected with the arm for swinging the same in one direction, a spring for moving the arm in the opposite direction and a spring for moving the core of the said solenoid to an extended position when the 110 said solenoid is deenergized.

2. Printing telegraph including a key selecting switch comprising arcuate upper and lower guides, spaced contacts located between the guides, key actuating magnetic 115 means connected with the contacts, a pivoted contact arm arranged to swing between the guides and movable upwardly and downwardly, a solenoid having a core forming a pivot for the arm or member and adapted 125

131

when the solenoid is energized to move the arm or member downward, a spring for automatically moving the arm or member upwardly when the solenoid is deenergized, 5 a solenoid having a core connected with the arm or member for swinging the same and springs connected with the said cores for moving the same to their extended positions, the spring of the core which constitutes the 10 pivot of the arm being of greater strength than the other spring.

3. Printing telegraph including separate sets of key actuating magnetic means, a magnet controlling switch comprising fixed and 15 relatively movable members, one of the members having spaced sets of contacts electrically connected with the separate sets of magnetic means and the other member having contacts arranged to contact with either 20 of the said sets of contacts, a key selecting switch having spaced contacts connected with the magnet controlling switch, a movable contact member coöperating with the contacts of the key selecting switch and electrically operated means for actuating the 25 said movable contact member and for operating the magnet controlling switch.

4. Printing telegraph including a magnet controlling switch comprising fixed and relatively movable members, spaced sets of contacts carried by one of the members, a single set of contacts located between the spaced sets of contacts, key actuating magnetic means arranged in separate sets and electrically connected with the separate sets of contacts carried by one of the members of the 30 said switch, a key selecting switch having spaced contacts connected with the single set of contacts of the magnet controlling switch, a movable arm or contact coacting with the contacts of the key selecting switch, magnetic means for actuating the movable member of the magnet controlling switch, a main line circuit, an induction coil having 35 its primary winding in circuit with the main line circuit and its secondary winding operatively connected with the said magnetic means, a local interrupted circuit and a sending induction coil having its primary winding in the local circuit and a secondary winding in the main line circuit and separate sets of operating devices having means for closing the main line circuit, one of the said sets being also provided with means for closing 40 the local circuit.

5. Printing telegraph including separate sets of key actuating magnetic means, a key selecting switch having contacts, a magnet controlling switch having separate sets of 45 contacts connected with the magnetic means and operable to connect either set of magnetic means with the key selecting switch contact, a movable contact member coacting with the contacts of the key selecting 50 switch, a main line circuit connected with 55

the key selecting switch, a receiving induction coil having its primary in the main line circuit and its secondary connected with the operating means of the magnet controlling switch, a local sending circuit, a sending induction coil having its primary in the local sending circuit and its secondary in the main line circuit and separate sets of operating means for closing the main line circuit and the local circuit. 70

6. Printing telegraph including separate sets of key actuating magnetic means, a magnet controlling switch comprising fixed and relatively movable members, one of the members being provided with spaced sets of contacts connected with the said magnets and the other member being provided with a single set of contacts located between the spaced sets of contacts and arranged to engage either set, a lever connected with the movable member of the said switch, means for automatically moving the lever in one direction and magnetic means for actuating the lever in the opposite direction. 75

7. Printing telegraph including separate sets of key actuating magnetic means, a magnet controlling switch comprising fixed and relatively movable members, one of the members being provided with spaced sets of contacts connected with the said magnetic means and the other member being provided with a single set of contacts located between the spaced sets of contacts and arranged to engage either set, a lever connected with the movable member of the 90 said switch, mechanical means for automatically moving the lever in one direction and magnetic means for actuating the lever in the opposite direction, means for locking the lever against movement after it has been actuated by the magnetic means, a key selecting switch having contacts connected with the single set of contacts of the magnet controlling switch, a movable member coacting with the contacts of the key selecting switch, and means for operating said movable member, said movable member being adapted to release the said lever of the magnet controlling switch when moved to its initial position. 95

8. Printing telegraph including separate sets of key actuating magnetic means, a magnet controlling switch comprising fixed and relatively movable members, one of the members being provided with spaced sets of contacts connected with the said magnetic means and the other member being provided with a single set of contacts located between the spaced sets of contacts and arranged to engage either set, a lever connected with the movable member of the said switch, means for automatically moving the lever in one direction and magnetic means for actuating the lever in the opposite direction, a spring actuated lever arranged to 100 105 110 115 120 125 130

automatically engage the said lever for locking the latter against movement after the same has been actuated by the magnetic means, a key selecting switch including contacts connected with the single set of contacts of the magnet controlling switch and a movable member coacting with the contacts of the key selecting switch, and arranged to engage the spring actuated lever for moving the same out of engagement with the other lever.

9. A printing telegraph system including a key selecting switch having contacts, an oscillating arm coacting with said contacts, magnetic means operably connected to said arm, a line circuit on which the said magnetic means are arranged, a single common resistance on said circuit and operating devices connected with varying amounts of 20 said common resistance for closing a local circuit, a sending induction coil having its primary in the local circuit and its secondary in the main line circuit, a receiving induction coil having its primary in the main 25 line circuit and electrically operated means connected with the secondary of the receiving induction coil for operating the key selecting switch.

10. Printing telegraph including separate sets of key actuating magnetic means, a key selecting magnet provided with contacts, a movable contact member coacting with the contacts of the said switch, a magnet controlling switch for connecting either 35 set of the magnetic means with the contacts of the key selecting switch, a main line circuit, magnetic means in the main line circuit for actuating the said movable member, a resistance in the main line circuit, 40 conducting wires extending from the resistance and having pairs of branches provided with contacts, separate sets of operating devices having contacts coacting with the contacts of the said branches for closing 45 the main line circuit through the resistance, a local circuit having contacts arranged to be closed by one set of the operating devices, a sending induction coil having its secondary in the main line circuit and its 50 primary in the local circuit, a receiving induction coil having its primary in the main line circuit, and electrically operated means connected with the secondary of the receiving induction coil for operating the magnet 55 controlling switch.

11. Printing telegraph including separate sets of key actuating magnetic means, a key selecting magnet provided with contacts, a movable contact member coacting with the 60 contacts of the said switch, a magnet controlling switch for connecting either set of the magnetic means with the contacts of the key selecting switch, a main line circuit, magnetic means in the main line circuit for actuating the said movable member, a re-

sistance in the main line circuit, conducting wires extending from the resistance and having pairs of branches provided with contacts, separate sets of keys having roller contacts arranged to engage the contacts of the said branches for closing the main line circuit, a local circuit having pairs of contacts arranged to be engaged by the roller contacts of one set of keys for closing the local circuit, a sending induction coil having its primary in the local circuit and its secondary in the main line circuit, a receiving induction coil having its primary in the main line circuit and electrically operated means connected with the secondary of the receiving induction coil for operating the magnet controlling switch.

12. Printing telegraph including carriage actuating means comprising a magnetic means having a horizontally movable core, 85 upper and lower fixed rack bars, upper and lower movable rack bars arranged in spaced relation with the fixed rack bar and pinions meshing with the said rack bars, the lower pinion being connected with the 90 core of the magnetic means and the upper pinion being connected with the lower movable rack bar.

13. Printing telegraph including a key selecting switch having spaced contacts, a movable member coacting with the said contacts, a resistance, a main line circuit in which the resistance is arranged, a magnet arranged in the main line circuit for actuating the said member, operating devices for closing the main line circuit through the resistance, a separate operating device for closing the main line circuit past the resistance for moving the said member beyond the contacts of the key selecting switch, a 100 terminal contact arranged within the path of the said member, a carriage actuating circuit in which the terminal contact is arranged and means in the last named circuit for operating the carriage.

14. A printing telegraph system including a main line circuit, transmitting means and recording means arranged on said circuit, a movable record receiving member, an electrically operated movable contact closing member on said circuit adapted to be operably connected with said record receiving member, a movable power transmitting member operated by said circuit, substantially parallel with said record receiving member 115 and movable power multiplying means between said transmitting member and said record receiving member.

15. A printing telegraph system including a main line circuit, transmitting means arranged on said circuit, recording means on said circuit, a movable record receiving member, an electrically operated movable contact closing member on said circuit adapted to be operably connected with said 125 130

receiving member, movable power transmitting means operated by said circuit, and parallel with said record receiving member and separate therefrom, a fixed rack bar 5 parallel thereto and in spaced relation with said means, another fixed parallel rack bar at a still greater distance from said record receiving member and beyond the first mentioned rack bar and in engagement with said 10 power transmitting means, a movable rack bar carrying means at one side to engage with said power transmitting means and having means at the other side to engage with the first mentioned rack bar and with 15 the record receiving member.

16. A printing telegraph mechanism including upper and lower sets of recording keys, a local battery, a plurality of contacts, upper and lower sets of key actuating magnets connected to one side of said battery, means for connecting either the upper or lower set of magnets to said contacts, an arm connected to the other side of said battery and adapted when actuated to engage 20 one of said contacts, transmitting keys, and means under the control of said transmitting keys for actuating said first named means and said arm.

17. A printing telegraph mechanism including upper and lower sets of recording 30

keys, a local battery, a plurality of contacts, upper and lower sets of key actuating magnets connected to one side of said battery, means for connecting either the upper or lower set of magnets to said contacts, an 35 arm connected with the other side of said battery and adapted when actuated to engage one of said contacts, an upper set of transmitting keys, means under the control of said keys for actuating said arm, a lower 40 set of transmitting keys controlling said arm actuating means, and means under the control of said lower set of keys for actuating the means for connecting either the upper or lower set of magnets to said contacts. 45

18. A printing telegraph mechanism including upper and lower sets of transmitting keys, upper and lower sets of recording keys, a recording key selecting switch 50 under the control of both sets of transmitting keys, and means under the control of one set of transmitting keys for connecting either set of recording keys to said switch.

In testimony whereof I affix my signature in presence of two witnesses.

EINAR G. C. LOFGREN.
